UNITED STATES PATENT OFFICE.

ISIDOR J. KUSEL, OF CHICAGO, ILLINOIS.

COIN BANK.

Application filed February 17, 1922. Serial No. 537,257.

My invention relates to coin banks particularly adapted for use in connection with savings coins in banking institutions, the coin bank being taken by the depositor and used to collect savings which are later deposited in the banking institution.

One of the objects of the invention is to provide a simple, practical and advantageous construction of coin bank of the class 10 specified.

Another object of the invention is to arrange for the use of a time piece in connection with the bank.

Another object of the invention is to arrange for the simple and practical mounting of the time piece in connection with the bank.

Another object of the invention is to provide ready access to the time piece for the purpose of winding the same or for other purposes, and also to arrange for the ready removal of the time piece for purposes of repair and otherwise.

In the accompanying drawings Fig. 1 is 25 a front view of a coin bank embodying my present invention;

Fig. 2 is a longitudinal section of the same;

Figs. 3 and 4 are cross sections taken on 30 lines 3-3 and 4-4, respectively, in Fig. 2;

Figs. 5 and 6 are respectively a plan view and edge elevation of a holding device for retaining the time piece in proper position in connection with the bank.

Referring to the drawings, I show a coin bank comprising a casing 1 which is preferably made of metal and is preferably cylindrical in cross section, as shown in Figs. 3 and 4. Both ends of this casing are open. 40 One end, the left hand end referring to Fig. 2, is provided with and preferably closed by a time piece 2 which may be in the form of a watch of any suitable or preferred construction. As any one of a variety of commercial watches at present on the market 45 may be used, no description of said time piece is made herein, other than to state that the watch is preferably of the stem winding variety with a winding member 3 for winding and setting the hands, and is also provided with an open face having a crystal 4. Said time piece 2 is preferably held detachably in position at said open end of the casing 1, a convenient arrangement being 50 to provide the casing with an annular lip 5 adapted to engage the case portion 6 of

said watch 2, and hold the same against outward movement. Means for temporarily or detachably retaining the watch in said position are also provided, a convenient arrangement being to arrange a ring or annulus 7 within the casing 1, immediately in the rear of the watch 2, so that it will back and preferably be in contact with the rear of said watch 2. The annulus or ring 7 is 60 split, as shown in Fig. 5, so that it may be compressed and reduced in size, thereby permitting it to be readily inserted into and withdrawn from the interior of the casing 1. There are projections 9-9 on the interior of the casing 1 for holding the annulus 7 in position against the watch 2, said projections being formed either by rivets 10-10 or by simply making indentations 70 in the casing walls. The annulus 7 has its 75 ends provided with laterally projecting portions or prongs 7^a-7^a and these may be grasped either by the fingers or by a pair of pincers, as shown in Fig. 6, to move the ends together and thereby reduce the size 80 of said annulus and permit it to be freed from the projections 9 and so removed from the casing 1.

Thus the watch 2 may be put in position at the end of the casing 1 so as to fill and close the opening thereof and be held in such position by the annulus 7. The face of the watch is exposed as shown in Fig. 1, so that it may be readily seen and serve as a time piece. To remove the watch the annulus 90 7 is removed, thereby permitting the watch to be moved out of the other open end at the right hand side of the casing 1 (Fig. 2).

The casing 1 is preferably provided with an aperture through which the stem 3, or 95 rather the shank or collar portion 3^a of said stem may fit. This permits the stem 3 always to be exposed so that the watch may be wound whenever desired.

The other open end of the casing 1, that is 100 the right hand end referring to Fig. 2, is provided with a closure 11, preferably in the form of an annular plate having an annular flange 12 fitted closely within the bore of the casing 1. For temporarily locking this closure in position, a prong 13 is shown on the casing 1, adapted to fit into an aperture in the flange 12 and the closure 11 is shown provided with a lock 14 having a bolt 15 adapted to engage a prong 16 on the casing 105 110 115 1. The lock 14 is controlled by a key 17 adapted to enter a key aperture in said

closure 11, whereby the bank may be locked and unlocked to permit the coins to be withdrawn when it is desired to deposit them or otherwise.

5 A coin slot 18 is shown on the closure 11 for the admission of coins of various denominations. If desired a coin slot 19 may be provided in the casing 1, as shown in Fig. 2.

10 The bank is preferably provided with supporting legs or standards 20-20 by which it may be held against rotation when set in position, and also by which the front or watch end may be tilted upward so as to more readily display the watch face.

15 These legs or standards may be conveniently formed by a piece or strip of metal bent as desired and secured by rivets 21.

20 It will be seen that the device may be readily used both as a savings bank and also as a time piece; also that the time piece may be readily inserted into and withdrawn from position and securely held while in such position, also that there is no interference with the winding or operation of the time piece nor any likelihood of any interference 25 with it by the coins or otherwise.

It will be understood that changes and modifications may be made without departing from the spirit of the invention.

30 What I claim is:

1. A coin bank comprising a cylindric casing open at its opposite ends, a time piece fitted into one end of the casing so as to

form a closure therefor, a removable closure for the other open end of the casing, and 35 means for holding the time piece temporarily in position, said means comprising a split ring arranged within the casing and adapted to engage the back of the time piece.

2. A coin bank comprising a cylindric 40 casing open at its opposite ends, a time piece fitted into one end of the casing so as to form a closure therefor, a removable closure for the other open end of the casing, and means for holding the time piece temporarily in 45 position, said means comprising a split ring arranged within the casing and adapted to engage the back of the time piece, said split ring having its separated ends bent toward the other open end of the casing to permit 50 them to be grasped by an opening tool.

3. A device of the class specified comprising a cylindric casing having its opposite ends open, a time piece arranged within the casing and closing one of said open ends, 55 means for holding the time piece detachably in position and a movable closure for temporarily closing the other end of the casing and locking means for said closure, said time piece being removable through the opening 60 closed by said closure.

In witness whereof, I hereunto subscribe my name this 9th day of February, A. D., 1922.

ISIDOR J. KUSEL.
